D789,872 S * 6/2017 Schoeppner D12/521
D817,258 S * 5/2018 Kikuchi D12/521

(71) Applicant: **SUMITOMO RUBBER
INDUSTRIES, LTD.**, Hyogo (JP)

(72) Inventor: **Mari Mishima**, Kobe (JP)

(**) Term: **15 Years**

* cited by examiner

(21) Appl. No.: **35/503,464**

Primary Examiner — George D. Kirschbaum

(22) Filed: **Jan. 30, 2017**

Assistant Examiner — Joseph J Kukella

(80) **Hague Agreement Data**

Int. Filing Date: **Jan. 30, 2017**

(57) **CLAIM**

Int. Reg. No.: **DM/094535**

The ornamental design for a tire for automobile, as shown and described.

Int. Reg. Date: **Jan. 30, 2017**

Int. Reg. Pub. Date: **Aug. 4, 2017**

(51) **LOC (11) Cl. 12-15**

(52) **U.S. Cl.**

USPC **D12/521**

(58) **Field of Classification Search**

USPC D12/505, 519, 521-524, 533-567

DESCRIPTION

CPC B60C 11/0302; B60C 2011/0358; B60C
2011/0374
